UNITED STATES PATENT OFFICE.

IRWIN DAVIS, OF KIRKSVILLE, MISSOURI.

SUCTION VENTILATOR.

Application filed May 21, 1925. Serial No. 31,907.

My invention relates to improvements in suction ventilators and has for its object to provide a simple and inexpensive, yet a highly advantageous construction which is such as to cause air currents to create an upward suction through the ventilating pipe.

With the foregoing in view, the invention resides in novel subject matter hereinafter described and claimed. The description being supplemented by the accompanying drawing.

Fig. 1 is a side elevation of a ventilator constructed in accordance with my invention.

Fig. 2 is a top plan view.

Fig. 3 is a vertical sectional view.

Fig. 4 is a horizontal section on line 4—4 of Fig. 3.

In the drawings above briefly described, the numeral 1 designates a foul air discharge pipe adapted to communicate with a foul air outlet from a building or chamber to be ventilated. A vertically disposed sheet metal wall 2 surrounds the upper portion of the pipe 1 and extends a considerable distance above and below the upper extremity of said pipe the extension being substantially equal in both directions from the extremity to eliminate down draft. The wall 2 is spaced from the pipe 1 in parallel relation thereto, to provide an unusually large comparatively unobstructed free air space and a plurality of substantially radial vanes 3 extend between the pipe and wall to divide the space into a plurality of vertical air ducts. While the upper ends of vanes 3 terminate about even with the upper end of pipe 1, the lower ends thereof, extend below the wall 2 and are preferably bevelled toward the pipe, as indicated at 4, thereby providing means for trapping horizontal air currents and directing them upwardly between the pipe 1 and wall 2, so as to create a suction through the pipe.

To form vanes 3, I preferably bend a plurality of metal plates into a U-shaped form in horizontal section, as seen in Fig. 4, the central portions of said plates being secured by rivets or the like at 5 to the pipe 1, while the edges of said plates, forming the outer portions of vanes 3, are bent laterally outward as at 6, and are secured by

bolts 7 or other means, against the inner side of wall 2. The several plates thus provide for supporting the wall upon the pipe 1 as well as dividing the space between said pipe and wall into vertical air ducts.

Within the upper portion of the wall 2 and spaced from said wall is a substantially conical cap 8 which is preferably provided with a depending corrugated flange 9 around its lower end. Through forming the base of the conical cap of only slightly greater diameter than the pipe 1, no obstruction is formed to prevent upward passage of air. This flange is spaced above pipe 1 and is provided with circumferentially spaced notches 10, through which the inner ends of radial arms 11 extend, said ends being bent upwardly and secured to the lower side of cap 8, as indicated at 12. The outer ends of the arms 11 are downwardly bent as at 13, and secured by bolts or the like, 14, to the inner side of the wall 2. The upper end portion 15 of this wall is preferably inclined inwardly and corrugated as indicated at 16 and is disposed in substantially parallel relation with the wall of cap 8 to effect a strong suction and to further render the ventilator weather-proof.

By providing a ventilator as shown, air currents in all directions will create an upward suction through pipe 1, and a device is provided which will be absolutely weather-proof, due to the height of the wall 2, extending above and below the upper terminal of the pipe 1 and the conical cap 8 located within the projecting upper end of said wall.

Excellent results have been obtained from the details disclosed, and they are therefore preferably followed, but within the scope of the invention as claimed, numerous minor changes may be made.

I claim:

A ventilator comprising a foul air discharge pipe, a continuous wall spaced outwardly from and concentric with said pipe, said wall extending substantially equal distances above and below the upper end of said pipe and having an inwardly upwardly inclined upper end, a substantially conical shaped cap spaced above the upper end of the pipe and having a depending annular flange at its lower end, the base of said cap being of greater diameter than the pipe, a series of

circumferentially spaced brackets connecting the lower end of said cap and adjacent portions of the wall, a set of vanes extending vertically between and rigidly connecting the pipe and wall, said vanes being substantially V-shaped in cross section and having their intermediate portions secured to the pipe and oppositely extending flanges

attached to said wall, and portions of said vanes being extended below the wall to 10 deflect air currents upwardly between the discharge pipe and said continuous wall.

In testimony whereof I have hereunto affixed my signature.

IRWIN DAVIS.
